METALLIC MESH MATERIAL
Olli S. Koskinen, 6236 Bloomfield Glens,
West Bloomfield, Mich.
Filed Aug. 18, 1960, Ser. No. 50,438
4 Claims. (Cl. 29—183)

This invention relates to mesh construction and to the method and apparatus for making the novel mesh material.

It is a particular object of this invention to provide an improved type of mesh material that is formed by a continuous, economical, simplified, one-step shearing operation.

It is another object of this invention to provide a novel mesh material that is formed by a single step shearing operation applied to an inexpensive, continuous sheet of relatively thin metallic or similar material.

It is still another object of this invention to provide a mesh material formed by a novel shearing process that permits the formation of outwardly extending V's or wing-like, projecting surfaces on either one or both sides of the sheet of stock, which V's are curled so that one V overlies the spaces from which adjacent V's are cut from the sheet. The V's are both cut and curled by a shear type of cutting and forming tool. The character of the mesh can be readily varied over a wide range by selecting different thicknesses of sheet stock and by varying the spacing of the successive shear cuts through the sheet stock and by forming the projections on one or both sides of the sheet.

It is another object of this invention to provide a novel sheet of mesh material having smooth edged border portions encircling a mass of evenly spaced, outwardly extending, curled, projections that present a mesh sheet of pleasing appearance that is extremely flexible for rolling into a coil or any other shape and wherein the curled outwardly extending projections provide the optimum in baffling structure for filtering purposes.

Other objects and advantages of this invention will become readily apparent from a reading of the following specification and a consideration of the related drawings wherein:

FIG. 1 is a fragmentary vertical sectional view of one form of apparatus for making a sheet of metallic mesh embodying this invention;

FIG. 2 is a fragmentary vertical sectional view taken along the line 2—2 of FIG. 1;

FIG. 3 is a fragmentary elevational view of one side or face of a sheet of mesh material embodying the invention shown in FIGS. 1 and 2;

FIG. 4 is a fragmentary sectional elevational view taken along the line 4—4 of FIG. 2;

FIG. 5 is a fragmentary side elevational view of a modified form of this invention;

FIG. 6 is a top plan view of the modified form of the invention shown in FIG. 5, the view being taken looking in the direction of the arrow 6 of FIG. 5;

FIG. 7 is an end elevational view of the FIG. 6 modified form of this invention, the view being taken in the direction of the arrow 7 of FIG. 5; and

FIG. 8 is a side elevational view of an internal combustion engine air cleaner having a filter element formed from a rolled coil of metallic mesh material embodying this invention.

FIGS. 1, 2 and 4 of the drawings show apparatus for forming a metallic mesh sheet M in accordance with one form of this invention. The sheet of mesh M formed by this apparatus is shown in FIG. 3 in particular. With the apparatus shown, a sheet of relatively thin metallic foil 10, such as aluminum or stainless steel, or the like, is passed upwardly between the friction drive rolls 11 and

2

12. The drive rolls 11, 12 each carry toothed gear sectors 11a and 12a that provide the means for actuating the rolls 11, 12 through the oscillatable drive links 13 and 14, respectively. The drive links 13 and 14 each have a hooked end 13a and 14a, respectively, that is adapted to drivingly engage the teeth of the associated gear sector 11a or 12a during oscillation of the links 13 and 14 by the oscillatable crank arms 15 and 16. Cranks 15 and 16 are pivotally supported at 17 and 18, respectively, and are oscillatably driven by reciprocating piston rods 19 and 20. The free ends of the oscillatable cranks 15 and 16 are connected by pivot pins 21 and 22 to the sets of cutter bars 23 and 24, respectively.

The cutter bars 23, 24, which are identical in size and shape, but arranged in opposed relationship, are triangularly shaped in cross sectional configuration. These cutter bars 23, 24 are slidably supported in mating grooves 25 formed in the table 27. Preferably the lower edges of the cutter bars are perpendicular to each other as shown in FIG. 2. This cuts a 90° V out of the sheet. A clamping bar 28, or similar mechanism, can be applied to the top of the cutter table 27 to retain the cutter bars 23, 24 in their mating table grooves 25. The table 27 has a slot 29 extending therethrough to receive the sheet 10 of stock material 10 as it is passed upwardly by the friction drive rolls 11, 12. Slot 29 in table 27 is positioned so that it will position the sheet stock 10 in the path of the reciprocating cutter bars 23, 24.

The cutting ends 23a, 24a of the cutter bars 23, 24 slope upwardly and rearwardly as clearly shown in FIGS. 1 and 4 to constitute forming tools which cause an outward curling of the projections 31 and 32 as the cutter bars 23, 24 are alternately reciprocated through the sheet stock 10 to shear the wings 31, 32 from the sheet stock.

As the piston rod 19 is drawn towards the left the crank 15 is turned counterclockwise and this movement of the crank 15 causes the drive link 13 to be pulled towards the left such that hooked end 13a of drive link 13 will engage the adjacent tooth on the gear sector 11a and thereby cause a partial rotation of the friction drive roller 11. At the same time that the drive roller 11 is being rotated counterclockwise the cutter bars 23 are being moved towards the withdrawn position 23c which is shown in broken lines in FIG. 1. Due to synchronization of the drive means for the piston rods 19 and 20, the crank 16 will be oscillated towards the left at the same time that the cutter bars 23 are being withdrawn from the sheet stock 10 and by the time the cutter bars 24 reach the position of the sheet stock 10 the friction drive roll 11 has elevated the sheet 10 to such a position that the cutter bars 24 may then pierce the sheet 10 and form a set of leftwardly extending curled wings 31. After cutting of the wings 31 by the cutter bars 24, the piston rod 20 is drawn towards the right so as to actuate crank 16 in a clockwise direction and at the same time begin rightward movement of the cutter bars 24 and rightward movement of the drive link 14. The hooked end 14a of the drive link 14 will engage a tooth on the geared sector 12a and thereafter rotate the friction roller 12 in a clockwise direction so as to cause elevation of the sheet stock 10 so as to position sheet material in the path of the cutter bars 23 which will thereafter be actuated to shear a set of rightwardly extending curled wing-like projections 32 from the sheet stock 10. As a result of repetition of the afore-described method of operation of the shearing apparatus, a sheet of mesh material having a configuration such as is shown in FIGS. 1 through 4 will be formed.

It will be noted from FIG. 1 that the wing-like projections 31 and 32 are arranged in staggered vertical relationship on opposite sides of the mesh sheet M, so that the V's on one side of the sheet are opposite the spaces

between the V's on the opposite side of the sheet. FIGS. 2 and 3 clearly show the peculiar arrangement of the projections 31 on one side of the mesh sheet, it being understood that there is a similar arrangement of wing-like projections 32 on the opposite side of the sheet in the spaces between the projections 31 as clearly shown in FIG. 1. Each of the V's is curled so that the surface of the V lies in a cylindrical surface, the axis of which is parallel to the line which joins the ends of the arms of the V at their roots, that is at the points where the arms remain attached to the sheet. As used herein, cylindrical has its geometric meaning, which includes any surface defined by the path of any closed planar curve moving parallel to itself in a substantially straight line. Preferably the V's occupy about 180° of this cylindrical surface so that the points of the V's are substantially parallel to the roots of the arms. See FIGS. 1 and 2. Also each V is curled to overlie a plurality of spaces from which the V's above it were cut. The combined effect of the staggering or opposite spacing and this overlie provides a particularly thick and effective baffle and filter arrangement in which one set of baffles on one side of the sheet is disposed at a substantial distance from the baffles on the opposite side, and opposite their interstices. It will be noted from FIG. 3 that the vertically arranged rows of projections 31 are attached to solid strips of sheet material 33 and that there is a border 34 of solid material around the sides of the mesh sheet M. Openings of substantially triangular shape 36 are formed at the lower end of the columns of wing-like projections 31, 32 as clearly shown in FIG. 3. A smooth unperforated edge 37 is also provided at the lower edge of the mesh sheet M so that the mesh sheet is easy to handle and can be readily mounted in a frame or support by means of its unperforated smooth edge border that extends completely around the mesh area.

FIGS. 5, 6 and 7 show a modified form of this invention wherein the mesh sheet M' is provided with outwardly extending curled V's 51 that extend from only one side of the sheet M'. Obviously such a modified form can be prepared by using only a single set of cutter bars that enter the sheet stock from only one side thereof rather than from opposite sides thereof. This particular formation may be particularly advantageous in certain installations although it does not provide the multiplicity of filtering elements that are supplied in a sheet such as the doubled sided sheet M of FIGS. 1 through 4.

FIG. 8 shows the incorporation of a coil of mesh material of the type disclosed in FIGS. 1 through 4 and 5 through 7 as the filter cartridge of an internal combustion engine air cleaner. The air cleaner 61 has an inlet pipe 62 and an outlet pipe 63. Air entering the interior of the cleaner 61 through the inlet pipe 62 must pass through the coil of metallic mesh 64 before passing outwardly through the outlet pipe 63 to the engine intake manifold. The filter cartridge 64 which is formed of mesh material

embodying this invention provides a very effective dry filter that can be provided at a minimum cost and will function with maximum efficiency.

I claim:

5 1. An integral mesh including a sheet of self-sustaining material having a series of V's cut from nested, contiguous portions of the sheet with the ends of the arms of the V's left attached to the sheet so that the portion of the material including said series consists entirely of said V's, each V being displaced out of the original plane of the sheet and disposed in a substantially cylindrical surface whose axis is parallel to the line joining the attached ends of the arms of the V.

15 2. An integral mesh including a sheet of self-sustaining material having a series of V's cut from nested, contiguous portions of the sheet with the ends of the arms of the V's left attached to the sheet so that the portion of the material including said series consists entirely of said V's, each V being displaced out of the original plane of the sheet and disposed throughout about 180° of a substantially cylindrical surface whose axis is parallel to the line joining the attached ends of the arms of the V.

20 3. An integral mesh including a sheet of self-sustaining material having a series of V's cut from nested, contiguous portions of the sheet with the ends of the arms of the V's left attached to the sheet so that the portion of the material including said series consists entirely of said V's, each V being displaced out of the original plane of the sheet and formed to overlie a plurality of spaces from which other individual V's have been cut.

25 4. An integral mesh including a sheet of self-sustaining material having a series of V's cut from nested, contiguous portions of the sheet with the ends of the arms of the V's left attached to the sheet so that the portion of the material including said series consists entirely of said V's, each V being displaced out of the original plane of the sheet and disposed in a substantially cylindrical surface whose axis is parallel to the line joining the attached ends of the arms of the V and alternate V's being on opposite sides of said plane so that a V on one side is opposite the space between adjacent V's on the other side.
